UNITED STATES PATENT OFFICE.

JOHN W. SHEPHERDSON, OF WORCESTER, MASSACHUSETTS, ASSIGNOR TO MORGAN CONSTRUCTION COMPANY, OF WORCESTER, MASSACHUSETTS, A CORPORATION OF MASSACHUSETTS.

ART OF ROLLING METAL.

Application filed December 18, 1924. Serial No. 756,723.

The present invention relates to the art of rolling metal, into bars, rods, plates, etc., of varying cross-section,—the present application being a continuation, in part, of my 5 cPending application, Serial No. 557,467, filed April 29, 1922.

In one of its aspects, the invention relates particularly to the production of plates or sheets of relatively flat cross-section, and 10 involves improvements in the use and operation of the vertically disposed rolls that act on the edges of such material, simultaneously with its passages through adjoining horizontal rolls of a continuous mill,—the 15 object being to insure uniformity of section in the finished pieces from end to end, with the elimination of any deformation therein, except that caused by a pure rolling process.

In another of its aspects, the invention 20 relates to the production, by continuous rolling, of pieces of any desired cross-section, and involves departures from previous practices in the mode of driving and operating the initial rolls of any given train of horizontal rolls constituting a continuous or semi-continuous rolling mill,—the object being 25 to eliminate any deformation, except that caused by a pure rolling process, and also to increase the flexibility, and when desired, 30 the capacity, of the mill.

In the accompanying drawings,

Figure 1 is a diagrammatic plan view of a continuous edging mill, using both vertical and horizontal rolls, and so organized 35 and constructed as to embody the principles of my invention, and

Figure 2 is a similar view, showing the invention applied to a continuous train of horizontal rolls.

Like reference characters refer to like 40 parts in the different figures.

Referring first to Fig. 1, the edging mill may comprise, for example, a plurality of horizontal roll stands 1, 1, operating in conjunction with one or more stands of vertical edging rolls 2. The full line showing 45 at the left hand side of Fig. 1 indicates the adaptation of the invention to an arrangement wherein the edging rolls are disposed in advance of the horizontal rolls; the broken line showing at the right hand side 50 of the drawing is illustrative of the invention as applied to the disposition of the edging rolls between cooperating stands of horizontal rolls.

It has heretofore been the practice to drive the vertical edging rolls of a continuous edging mill in either one of two ways, namely, either by positive gearing from the horizontal rolls of the mill, at a speed bearing a 60 fixed relation to the speed of said horizontal rolls, or else by a ratchet drive. When the vertical edging rolls are disposed in advance of the horizontal rolls 1, as shown in full lines at the left hand side of Fig. 1, it has 65 heretofore been customary to employ this ratchet drive, in connection with which the material, as it first enters the edging rolls, is moved solely by the power applied through the ratchet. Afterwards, however, 70 the front end of the material is taken hold of by the horizontal rolls, and the tendency of these, under normal conditions, to move the bar at an increased speed is permitted by the ratchet drive of the edging rolls. The 75 effect therefore is to drag the material through the edging rolls, the latter rotating at a higher speed than that imparted thereto by the ratchet.

In other words, under these conditions, the 80 edging rolls derive their rotation not from the ratchet, but from the material itself, by reason of the tension therein produced by the more rapidly rotating horizontal rolls. This existence of tension in the material is 85 highly disadvantageous, since it involves, in addition to the desired reduction by rolling, a most undesirable and non-uniform reduction by stretching. For example, both the front and back ends of the finished piece 90 will be apt to have, under these conditions, a different section from the intermediate portion of the piece, since the reduction of this intermediate portion is accomplished by combined rolling and stretching, whereas no 95 stretching takes place on the two ends. It is the aim of the present invention to obviate this non-uniform treatment of the material by the creation and maintenance of rolling conditions in an edging mill which eliminate, as far as possible, the existence of tension in the material between the different stands of rolls,—thus obtaining the desired reduction wholly by the rolling action of the horizontal and vertical stands, respectively.

As shown in Fig. 1, the horizontal stands of rolls 1, 1 are adapted to be driven in the usual manner at progressively increasing speeds by bevel gearing 3, 3 from a main 110

driving shaft 4, the latter being connected to any suitable source of power, not shown. The edging rolls 2 in advance of the horizontal rolls 1, 1 are adapted to be driven wholly independently of said horizontal rolls, from a separate source of power, as for example, a variable speed motor 5, the latter, preferably having the speed-power characteristics of a compound wound direct current motor. Said separate independent driving means for the edging rolls 1, 1, (here shown as motor 5) is equipped, according to the invention, with a suitable device for indicating variations in the power required to drive the edging rolls 2, said device being here shown by way of example, as an ampere meter 6. Said separate individual driving means is also equipped, according to the invention, with a device, such as a rheostat 7, for varying the speed of the edging rolls, as desired.

As the material enters the mill, it is first acted upon solely by the edging rolls 2, and a short time interval elapses before the front end of the material enters between the next succeeding pair of horizontal rolls 1. In this interval, according to the invention, an observation or reading is taken from the device 6, as indicative of the power input of the rolls 2, required to accomplish the desired edgewise reduction of the piece. As soon as the piece has entered into the horizontal rolls 1, another reading or observation is taken from the device 6; and from a comparison of this second reading with the first, it is possible to establish in the mechanism the desired conditions of rolling, in the following manner:

If the power input indicated by the second reading is lower than the original reading, this is an indication that the material is being deformed under two influences in the edging rolls 2, namely, partly by rolling and partly by being drawn or stretched by the next succeeding higher speed horizontal rolls 1. This condition can be rectified immediately by manipulation of the speed control device 7, to increase the speed of the edging rolls 2 and thereby bring the power input shown on the indicating device 6 up to the original reading, thus insuring the deformation of the piece in the edging rolls 2 by rolling action alone, and eliminating entirely, in respect of edgewise reduction, any assisting influence of the horizontal rolls 1.

If, on the other hand, the second reading is higher than the original one, it can be inferred that the speed of the edging rolls 2 is too fast and that in addition to their rolling action on the piece, they are tending to push the same through the horizontal rolls 1. Under such conditions, the speed control device 7 can be manipulated to decrease the speed of the edging rolls 2, until

the power input reading corresponds to the original reading thus correctly regulating the relative roll speeds to insure the desired reduction in each stand by a pure rolling action.

70

The invention as above described is likewise applicable to the actuation and control of edging rolls which are located at an intermediate point in the mill, as indicated in broken lines at 2'. As before, said rolls are adapted to be driven separately and independently from the horizontal rolls 1 and 1' respectively, preceding and following, the mechanism being the same as provided for the stand of rolls 2, namely a variable speed motor 5', an ampere meter 6' and a rheostat 7'.

An initial reading is taken on the device 6' when the edging rolls 2' start to work on the front end of the piece of material, and a second reading is taken when said front end has been entered into the horizontal rolls 1'. After the rear end of the material passes beyond the horizontal rolls 1, a third reading is taken, indicative of the conditions existing in the material between the stands of rolls 1' and 2'. From these three readings, it is possible, by a simple calculation, to arrive at an approximately correct power input figure for the edging rolls 2', in respect of all similar succeeding pieces of material that are to be reduced by the same means to the same section as the first or trial piece.

Figure 2 discloses the same principle of operation as described above, in connection with the several stands of horizontal rolls 8, 8' of an ordinary continuous rolling mill. In this mill the horizontal rolls 8, 8, of the initial stand are driven by an independent variable speed motor 5, corresponding to the motor 5 of Fig. 1, and the horizontal rolls 8', 8', of the subsequent stands are driven in the usual way, at progressively increasing speeds, by bevel gearing 3, 3, from a main driving shaft 4. In precisely the same manner as in the edging mill of Fig. 1, the material entering the mill is first acted upon solely by the initial rolls 8, 8, and in the short time interval which elapses before the front end of the material enters between the next succeeding pair of rolls 8', 8', an observation or reading of the power input of the rolls 8, 8, may be taken from the ampere meter 6 of motor 5. Then when the piece has entered one or the other of the subsequent stands of rolls 8', 8', another reading or observation is taken from the device 6, and the comparison of this second reading with the first reading indicates whether or not the rolls 8, 8, are running at the proper speed to fulfill ideal conditions of rolling, i. e., reduction of the piece by a pure rolling action, in the absence either of stripping, or of pushing, or com- 130

pressing tendencies. If the two power input readings are not substantially the same, the speed control device 7 for motor 5 affords a means of either increasing or decreasing the speed of rolls 8, 8, as may be required, in order to make the second reading conform substantially to the first.

Furthermore, with this arrangement of separately driving a horizontal pair of rolls placed in advance of a continuous train and operable at adjustable speeds, an advantage is obtained in that said first pair of rolls can be made to deliver the stock selectively to any one of the succeeding pairs. For instance, when such a continuous mill is placed immediately adjacent to a heating furnace, the pusher bar of said furnace can only conveniently push the stock into the first pair of rolls, and under these conditions when it is desired to begin the reduction of the stock in a pair of rolls beyond the first or second pairs, it has heretofore been difficult to introduce the stock satisfactorily to the desired rolls, on account of the relatively slow speeds of the preceding non-operative or dummied roll stands. However, by the provision of an initial stand of rolls whose speed is adjustable, this difficulty can be overcome by speeding up said initial rolls to relate them properly to the roll speed of the stand selected for the commencement of rolling,—thus enabling the mill to operate at a greatly increased capacity under these conditions.

I claim,

1. In the production of relatively flat metal bars by continuous flatwise and edge-wise rolling, the improvement which consists in introducing a bar first to the edge-wise rolls, observing the power required for edge-wise rolling alone, and thereafter, in the continuous rolling operation on subsequent similar bars, by both edgewise and flatwise rolls, supplying power for said edge-wise rolling in accordance with said observation.

2. In the production of relatively flat metal bars by continuous flatwise and edge-wise rolling, the improvement which consists in introducing a bar first to the edge-wise rolls, observing the power required for edge-wise rolling alone, then observing the power input for edge-wise rolling of said bar when it is being acted upon by both edge-wise and flatwise rolls, and thereafter, for subsequent similar bars, adjusting said last mentioned power input to conform to the first observation.

3. In a continuous rolling mill, the combination with horizontal rolls and vertical

edging rolls, of means for independently supplying power to said edging rolls, and means for indicating any increase or decrease in the power input of said rolls during the continuous rolling operation, as compared to their power input when operating alone.

4. In a continuous rolling mill, the combination with horizontal rolls and vertical edging rolls, of means for independently supplying power to said edging rolls, means for indicating any increase or decrease in the power input of said rolls during the continuous rolling operation, as compared to their power input when operating alone, and means for adjusting the speed of said edging rolls during the continuous rolling operation.

5. In the art of rolling metal, by the action thereon of a continuous train of reducing rolls, the improvement which consists in rolling a piece of the material first in the initial roll stand alone of said train, observing the power required for the reduction of said piece by said initial roll stand, and thereafter in the continuous rolling operation on subsequent similar pieces of material by all the roll stands of said train, supplying power for the rolling in said initial stand in accordance with said observa- 90

6. In the art of rolling metal, by the action thereon of a continuous train of reducing rolls, the improvement which consists in rolling a piece of the material in the initial roll stand of said train and simultaneously observing the power required to effect the deformation taking place in said initial roll stand before the piece reaches the reducing pass in the next succeeding roll stand of said train, and thereafter adjusting the speed of the driving means of said first roll stand to maintain therein the same power input following the entrance of the piece into the pass of said next suc- 105

7. In the art of rolling metal, by the action thereon in a continuous mill of horizontal rolls and vertical edging rolls, the improvement which consists in introducing the material first to the vertical rolls, observing the power input required for the action on said material of the vertical rolls alone, and thereafter, for the continuous rolling operation on subsequent similar material, by both horizontal and vertical rolls, adjusting said power input to the vertical rolls to accord with said observation.

Dated this twelfth day of December, 1924.

JOHN W. SHEPERDSON.
